UNITED STATES PATENT OFFICE.

DWIGHT S. COLE, OF GRAND RAPIDS, MICHIGAN.

TURBINE.

1,037,440.

Specification of Letters Patent.

Patented Sept. 3, 1912.

Application filed March 21, 1910, Serial No. 550,629. Renewed January 2, 1912. Serial No. 669,125.

To all whom it may concern:

Be it known that I, DWIGHT S. COLE, a citizen of the United States of America, residing at Grand Rapids, in the county of Kent and State of Michigan, have invented certain new and useful Improvements in Turbine-Engines; and I do hereby declare the following to be a full, clear, and exact description of the invention, such as will enable others skilled in the art to which it appertains to make and use the same.

My invention relates to improvements in turbine engines, and more particularly to the type of such engines known as radial flow.

The objects of my invention are to provide a mechanism for the purpose which is simple, cheap and easy to construct, durable and efficient in operation, and in which the flowing elastic fluid exerts no axial or end-wise pressure upon the rotor or its shaft. These and other objects of my invention will more fully appear from the following description.

My invention consists essentially of the various novel features of construction, combination, and arrangement of parts herein-after more fully described and particularly pointed out in the claims, reference being had to the accompanying drawings illustrating a device embodying my invention, and the best mode contemplated by me of applying my invention in practice.

An engine constructed in accordance with my invention, comprises a casing having inlet and outlet pipe connections for conveying the steam or other elastic fluid into and out of its interior; bearings for a shaft; a shaft in the bearings and passing through the casing; a rotor within the casing secured to and carried by the shaft; annular rows of vanes or buckets upon and secured to both side faces of the rotor disk adjacent its periphery; a nozzle or nozzles, fixed to and leading from a steam supply chamber in the casing, in close proximity to the inner openings or inlets of one of the annular rows of vanes or buckets of the rotor, and adapted to discharge the fluid into the said row of buckets; a multiplicity of guide vanes or passages formed in the inner face of the circumferential wall of the casing, or in a part secured therein, exterior to the periphery of the rotor and adapted to receive the fluid, as it flows radially from the buckets on one side of the rotor, and guide it in a curved

path through a turn of substantially 180 degrees, or until it flows inwardly in a substantially radial direction into the inlets of another annular series of buckets on the opposite face and at the periphery of the rotor.

Additional sets of guide vanes, adjacent the side faces of the rotor and attached to or carried by the casing, may be employed to guide the flowing stream of steam into additional annular rows of buckets secured to or formed upon the side faces of the rotor to increase the compounding to any extent that may be found most satisfactory.

In the preferred embodiment of my invention, the rotor is constructed of two disks of comparatively thin plates of metal, of substantially the same dimensions and form, which are oppositely offset and spaced apart near their peripheries and secured firmly together and to a hub-piece by rivets, and have annular rows of buckets on the side faces thereof attached thereto by suitable means. In one alternative construction the rotor is constructed of a single disk of comparatively heavy plate metal properly formed for having the annular rows of buckets secured thereto by inserting the mounting portion of the buckets in closely fitting annular dove-tail grooves or channels formed in the side faces of the rotor.

In another alternative construction, the rotor is likewise formed of a single disk of comparatively heavy plate metal of proper form having the annular rows of buckets secured thereto on its side faces by through rivets of proper form, using buckets having the same form of mounting portion, and otherwise like or similar to the buckets employed with the first mentioned type of rotor construction.

The buckets of the rotor in my invention are designed to be made of suitable sheet metal formed and trimmed to shape for mounting by the action of suitable dies, and the shape of the several parts of the buckets is such that portions of each bucket of a row accurately fit and securely interlock with adjacent portions of the immediately preceding and immediately following buckets of the same row, so as to form practically tight side walls to the buckets to prevent steam loss therethrough and also to rigidly support the buckets in position against displacement by the centrifugal stresses produced by high rotational velocities.

It is also in accordance with the preferred embodiment of my invention that the guide passages exterior to the periphery of the motor be formed by milling into the solid metal of the inner face of a hoop, ring, or segment of suitable metal properly mounted in the casing. The preferred construction also embodies forming and mounting the side sets of guide vanes in substantially the same manner as that employed in forming and mounting the buckets of the rotor.

Referring now to the drawings: Figure 1 is a partial central longitudinal section of a turbine engine embodying my invention; Fig. 2 a section on the line 2-2 of Fig. 1; Fig. 3 a section on the line 3-3 of Fig. 1; Fig. 4 a detail in section on the line 4-4 of Fig. 3; Figs. 5, 6, and 7 enlarged views of a bucket of the rotor in different positions; Fig. 8 an inner face view of a portion 20 of the return guide vanes and passages secured to the casing opposite the periphery of the rotor; Fig. 9 a central vertical section on the line 9-9 of Fig. 8; Fig. 10 a partial central longitudinal section of a two-stage 25 turbine engine embodying my invention; Fig. 11 a section on the line 11-11 of Fig. 10; Fig. 12 a section on the line 12-12 of Fig. 11; Figs. 13 and 14 two views of a 30 bucket similar to that shown by Figs. 5, 6, and 7, but having different means of securing it to the rotor disk; Fig. 15 a section on the line 15-15 of Fig. 13; and, Fig. 16 a partial section of a rotor disk and its 35 buckets showing a modified means for attaching the buckets thereto.

Like numbers refer to like parts in all of the figures.

1 is the main casing of the turbine; 2 is the supply pipe for the steam or other elastic 40 fluid; 3 is the pipe for the escape of the exhaust or waste steam; 4 and 4 are the bearings for the main shaft 5; 6 is the rotor disk; 7 is the hub by which the rotor disk 6 is mounted upon and secured to the shaft; 8 is a stop or collar on the shaft 5 which engages the thread on the hub of the rotor disk 7 and thus firmly secures the rotor upon the shaft; 50 10 is a heavy washer or flange which aids in more firmly securing the disk of the rotor to its hub; 11 are the rivets which secure the rotor disk to the flange of its hub and to the flange or plate washer; 12, 13, and 14 are annular rows of buckets mounted on the side faces of the rotor disk 6; 15 are the rivets which respectively secure the buckets 12, 13, and 14 to the rotor disk and the guide vanes 23 to the segment 24; 16 is the annular 55 offset in the plates of the rotor disk 6; 17 is a part to which the steam supply pipe 2 is connected, containing a steam chamber and secured to the casing 1 by the screws 18; 19 is a nozzle discharging from the 60 chamber in part 17 toward the inlet open-

ings of the row of buckets 12 of the rotor; 20 is the segment or portion of a hoop or ring containing the reversing guide vanes 21 in its inner side; 22 is one of the screws by which the segment 20 is secured to the casing 1; 23 are guide vanes located opposite the side of the rotor disk 6; 24 is a segment for supporting the guide vanes 23; 25 is one of the screws which secures the segment 24 to the casing; 26 is one of the bolts which secures the parts of the casing together; 27 is the securing member of the bucket by which the same is located and secured in place, being provided with a conical hole 21 to receive the countersunk head of a rivet, 80 as shown; 28 is the impulse receiving member of the bucket; 29 is the outer side closing member of the bucket, projecting oppositely to the securing member 27 and from the opposite side of the impulse receiving member 28.

In the two stage modification shown in Figs. 10 to 15 inclusive, 1 is the casing; 2 the supply pipe; 3 the exhaust pipe; 4 the bearings; 5 the shaft; 6 a rotor; 7 a hub for the rotor; 8 a stop collar; 9 a screw thread; 10 a washer on the hub; 11 rivets; 12, 13, and 14 buckets secured to the rotor; 15 rivets to secure the buckets to the rotor and guide vanes 23^b to their support 24^b, all 95 substantially as heretofore described in the single stage form of my device.

30 is a partition or diaphragm which divides the interior of the casing into two chambers; 17^a is an annular distribution 100 chamber which conducts the steam from the supply pipe to an annular series of nozzles 19^a of the first or high pressure stage; 31 is the chamber in which the rotor and the other parts of the high pressure or first stage 105 mechanism are located; 32 is the disk of the first stage rotor; 33 is a hub which secures the rotor disk 32 to the shaft on which it is mounted; 34 is a nut engaging a thread 35 on the shaft 5 to fix the rotor hub on the 110 shaft; 36, 37, and 38 are annular rows of buckets secured to the side faces of the rotor disk 32; 21^a is a continuous annular 115 series of reverse guide vanes, formed in a ring 20^a, identical in character and location to the guide vanes 21 of Fig. 1; 22 is one of the screws which secures the ring 20^a to the casing; 39 is an annular row of guide vanes opposite the side of the rotor disk 32; 24^a is an annular plate upon which the row 120 of guide vanes 39 is mounted, this plate being secured in position in the casing by clamping it between the ring 20^a and the diaphragm 30; 40 is an annular row of nozzles, in the partition or diaphragm 30, 125 which discharge the steam from the chamber 31 into the annular row of buckets 12 on the rotor 6 in the second or low pressure stage of the machine; 43 is a spacing sleeve 130 on the shaft 5 between the hubs of the two 135

rotors; 44 is a suitable packing, as carbon, in the opening where the shaft 5 passes through the diaphragm 30.

41 is the chamber in which the rotor 32 of the low pressure or second stage mechanism is located, which mechanism also includes an annular series of return guide vanes 21^b in a ring 20^b, and annular guide vanes 23^b supported on an annular plate 24^b secured between the case and the ring 20^b by the screws 22. The buckets and vanes in this low pressure stage are somewhat larger than the similar parts of the first stage mechanism to accommodate the larger volume of the partially expanded steam therein.

Figs. 13, 14, and 15 show a modified bucket in respect to the fastening means only, in which the members 27^a are preferably made narrower than the outer side closing member 28^a, and are provided with dove-tail edges to enable them to be inserted in series in annular dove-tail grooves 42 in the rotor 32, as clearly shown in Fig. 10.

It will be noted that the securing member 27 of each bucket is convex at the free end to fit closely against the concave surface of the next adjacent bucket; and that as each bucket is secured in place, that surface of the securing member which forms a side wall of the following bucket, is fully exposed so that any elevation of the rivet head or other imperfection of its surface may readily be removed before the following bucket is put in place. Also that the side closing member 29 is concave at its free end which fits closely against the convex surface of the member 28 of the next adjacent bucket. Thus when the buckets of an annular row are all in place, each passage therethrough is closed on all four sides and smooth.

In operation, the steam or other elastic fluid is supplied under pressure to the steam chamber 17, or 17^a, as may be, and is discharged through the nozzles 19, or 19^a, which are preferably of the usual expanding type and thus discharge the steam radially and tangentially at a high velocity into the first series of buckets 12, or 36, on one side 50 of the rotor. The steam thence flows at high velocity into the return guide vanes 21 and from them radially and tangentially inward into the buckets 13, or 37, on the opposite side of the rotor from the nozzles and 55 thence between the side guide vanes 23, or 39, to the inner series of buckets 14, or 38, on the rotor. Obviously the annular rows of buckets on the sides of the rotor and the annular rows of side guide vanes may be 60 repeated or duplicated on either side of the rotor, as may be warranted.

It is also obvious that by the construction shown, a single nozzle or a multiplicity of nozzles up to full peripheral admission may 65 be used, as illustrated by the multiple stage

construction herein shown. So also the number of stages may be increased as desired, thus providing a considerable range of powers with a given diameter of rotor and case.

The bucket having dovetail fastening means and ports co-acting to secure the same are not claimed herein, but are reserved for a separate application in accordance with requirement for division.

What I claim is:—

1. A turbine engine, comprising two disk rotors, buckets on opposite sides of each of the said rotors, a case inclosing the rotors and having a partition between the rotors, 80 a nozzle in the case to admit steam radially to the first rotor, a nozzle in the partition to admit steam to the second rotor, and return guide vanes opposite the periphery of each rotor to radially return the steam escaping 85 from one side of each rotor to the other side of the same.

2. A turbine engine, comprising a case having a partition therein dividing the same into two separate compartments, a disk 90 rotor in each compartment, buckets on each side of each rotor, nozzles in the case and partition, to discharge steam radially outward into the buckets on one side of each rotor and guide vanes opposite the periphery of each rotor to return steam radially 95 inward to the other side of each rotor.

3. A turbine engine, comprising a case having a partition dividing the same into separate compartments, a disk rotor in 100 each compartment each having a single series of buckets on one side face and two concentric series of buckets on the other side face spaced apart, a nozzle in the case and a nozzle in the partition each adapted 105 to discharge steam radially outward into the first series of buckets of the respective rotor, guide vanes in the case opposite the periphery of each rotor to return steam to the outer series of buckets on the other side 110 of the respective rotor, and guide vanes between the concentric series of buckets of each rotor.

4. A turbine engine, comprising a disk 115 rotor, a single series of buckets on one side of the rotor, a nozzle to discharge steam outward through said buckets, return guide vanes opposite the periphery of the rotor, a series of buckets on the opposite side of the rotor and opposite the first named series of buckets to receive steam from the said guide vanes, a third series of buckets on the rotor and spaced apart from the second series, and guide vanes between the second and third series of buckets.

5. A turbine engine, comprising a disk 120 rotor, a casing inclosing the same, a series of buckets on one side of the rotor, a nozzle supported by the case near one side of the rotor and adapted to discharge steam out- 130

ward through said buckets, return guide vanes opposite the periphery of the rotor, two concentric series of buckets on the other side of the rotor and spaced apart, a series of guide vanes between the said two series of buckets, and an annular plate supporting the guide vanes and secured to the case.

6. A turbine engine, comprising a casing, a diaphragm in the casing, a disk rotor in each compartment of the casing, an annular steam chamber in the casing, an annular series of nozzles in the said chamber adapted to discharge steam outwardly, a circular series of buckets on the rotor surrounding the chamber and nozzles, a circular series of return guide vanes surrounding the rotor, two concentric series of buckets on the other side of the rotor and spaced apart, a circular plate clamped between the return guide vanes and the diaphragm side vanes on the plate, a circular series of nozzles in the diaphragm, return guide vanes, buckets on the rotor, side guide vanes, and a plate in the second compartment of the case.

7. A turbine bucket, comprising a middle member to receive the impulse and oppositely projecting members extending from opposite sides of the middle member, one of which is secured to the rotor and the other forming a side for the passage between two adjacent buckets.

8. A turbine bucket, comprising a middle member concave on one side and convex on the other side, a securing member extending from one side of said middle member and convex at the end to fit the concave side of an adjacent bucket, and an outer member projecting from the other side of the middle member and concave at the end to fit the convex side of an adjacent bucket.

9. A turbine bucket, comprising a mid-

dle member concave on one side and convex on the other side, a fastening member projecting from one side of the said middle member and at right angles thereto perforated to receive a rivet and also convex on the end to fit the concave side of an adjacent bucket, and an outer side member having a concave end to fit the convex side of an adjacent bucket.

10. A turbine bucket, comprising a member to receive the impulse concave on one side and convex on the other side, and a securing member projecting from the convex side of the said member at right angles thereto and perforated to receive a rivet.

11. A turbine engine, comprising two sheet metal disks secured to each other and having their edges oppositely offset and spaced apart, and a circular series of buckets secured to the outer face of the offset portion of each disk.

12. A turbine engine, comprising two sheet metal disks secured to each other, a hub in the axis of the disks, a flange and a washer on the hub at opposite sides of the disks, and rivets extending through the flange, the washer, and the disks.

13. A turbine engine, comprising two sheet metal disks secured to each other and having oppositely offset edges spaced apart, a circular series of buckets riveted to each disk, a nozzle to discharge steam outward into one series of buckets, and return guide vanes to direct the steam inward into the other series of buckets.

In testimony whereof I affix my signature in presence of two witnesses.

DWIGHT S. COLE.
